CLAIM

The ornamental design for a ceiling fan light glass, as shown and described.

DESCRIPTION

This application is related to U.S. patent application Ser. No. 29/730,561, filed on Apr. 6, 2020, currently pending.

FIG. 1 is a bottom perspective view of a ceiling fan light glass shown in the environment of a ceiling fan, showing my new design;

FIG. 2 is a top perspective view of the ceiling fan light glass of FIG. 1, having the ceiling fan environment removed;

FIG. 3 is a front view thereof;

FIG. 4 is a right side view thereof;

FIG. 5 is a rear side view thereof;

FIG. 6 is a left side view thereof;

FIG. 7 is a top view thereof; and,

FIG. 8 is a bottom view thereof.

Portions of the ceiling fan light glass and the ceiling fan environment are shown in broken lines, which form no part of the claimed design.

1 Claim, 5 Drawing Sheets
